COMBINED WALLET AND SAFETY CHAIN

Samuel Kitzes, New York, N. Y.

Application October 26, 1950, Serial No. 12,748

Term of patent 7 years

(Cl. D87—3)

To all whom it may concern:

Be it known that I, Samuel Kitzes, a citizen of the United States of America, residing in New York city, county of Kings, and State of New York, have invented a new, original, and ornamental Design for a Combined Wallet and Safety Chain, of which the following is a specification, reference being had to the accompanying drawing, forming part thereof, wherein,

Figure 1 is a front elevational view of a combined wallet and safety chain, showing my new design.

Figure 2 is an open perspective view of the combined wallet and safety chain shown in Figure 1, drawn on a smaller scale.

Figure 3 is a rear elevational view of Figure 1, drawn on a smaller scale.

I claim:

The ornamental design for a combined wallet and safety chain, substantially as shown.

SAMUEL KITZES.
